PIPING ATTACHMENT FOR SEWING MACHINES

Elmer T. Coates, Shrewsbury, Mo., assignor to
Angelica Jacket Company, St. Louis, Mo., a
corporation of Missouri

Application September 23, 1943, Serial No. 503,512

7 Claims. (Cl. 112—152)

This invention relates to piping attachments for sewing machines. The principal objects of the invention are to provide a piping attachment that can be readily mounted on and dismounted from the sewing machine without disorganization or alteration thereof, that will provide for both horizontal and vertical adjustment of the attachment relative to the machine, that will permit the attachment to be swung upwardly clear of the space between the head and the work table of the sewing machine without loss of either of said adjustments and that will provide a clear space for the operator's fingers in front of the needle and presser foot in the operative position of the attachment. The invention consists in the piping attachment and in the combinations and arrangements of parts hereinafter described and claimed.

In the accompanying drawing, which forms part of this specification and wherein like symbols refer to like parts wherever they occur:

Fig. 1 is a fragmentary front elevational view of a sewing machine provided with a piping attachment embodying my invention.

Fig. 2 is an enlarged view similar to Fig. 1.

Fig. 3 is an end elevational view of the parts shown in Fig. 2.

Fig. 4 is a horizontal cross-sectional view on the line 4—4 in Fig. 2.

Fig. 5 is a horizontal cross-sectional view on the line 5—5 in Fig. 2.

Fig. 6 is a vertical cross-sectional view on the line 6—6 in Fig. 2.

Fig. 7 is a vertical cross-sectional view on the line 7—7 in Fig. 3.

Fig. 8 is a plan view of a piece of fabric with the piping incorporated in the hemmed margin thereof; and.

Fig. 9 is a vertical cross-section on the line 9—9 in Fig. 8.

In the accompanying drawing, my invention is illustrated in connection with a sewing machine comprising a work table 1, an arm 2 overhanging said work table and terminating in a head 3, a presser foot 4 and needle 5 reciprocable in said head, and suitable work feeding elements 6 operating in openings 7 provided therefor in said work table below said needle and presser foot. This construction of sewing machine is well known and it is considered unnecessary to illustrate it in detail.

My piping attachment comprises a bracket 8 which is rigidly secured at its front end by means of a screw 9 to the end face of the sewing machine head 3 and has its rear end portion 10 off-

set outwardly relative thereto. A plate-like arm 11 is secured by a pair of vertically spaced horizontal screws 12 flatwise to the rear end portion of the bracket 8. The two screws 12 extend through an elongated vertical slot 13 in the rear end of the arm 11, whereby said arm may be adjusted vertically with respect to said bracket 8. A plate 14 covers the slot 13 and is clamped flatwise against the arm 11 by the heads of the screws 12. As shown in the drawing, the arm 11 has an opening 15 extending horizontally therethrough opposite the securing screw 9 for the bracket 8 so that a screw driver may be inserted through said opening to engage said screw.

Pivoted at one end by means of a horizontal pivot screw 16 to the lower front corner of the arm 11 is a plate-like arm 17 adapted for vertical swinging movement relative to the arm 11 parallel with the line of work feed of the sewing machine. In the operative position of the attachment, the pivotal arm 17 is swung downwardly into vertical position, rearward swinging movement of said arm being limited by means of a stop lug 18 thereon that is adapted to abut against the underside of the arm 11.

Mounted on a lateral extension 19 of the pivotal arm 17 at the free lower end thereof for horizontal adjustment relative thereto transversely of the line of work feed is a downwardly tapering tape folding tube 20. The tube 20 has a lateral extension 21 that is secured flatwise to the lateral extension 19 of the pivotal arm 17 by means of a pair of horizontally spaced screws 22 that extend through an elongated horizontal slot 23 in the tube extension 21 and are threaded into the arm extension 19 thereby permitting bodily adjustment of said tube crosswise of the line of work feed. A plate 24 covers the slot 23 and is clamped flatwise to the front face of the tube extension 21 by the heads of the screws 22.

At the lower end of the tape folding tube 20, the head opposing side wall thereof is continued downwardly in the form of a guide finger 25 that curves downwardly and outwardly, as at 25a in the direction of the line of work and terminates in a rearwardly extending horizontally disposed free end portion 25b that is disposed in the line of work feed just forward of the presser foot 4 and needle 5 and just above the feed elements 6 in the top of the work table 1. The free end 25b of the guide finger 25 has a tape receiving opening 26 extending vertically therethrough.

The tape A from which the piping B is formed is taken off of a supply roll 27 which is rotatably

mounted on a horizontal journal 28a provided therefor on the upper end of an upright 28 whose lower end is rigidly secured to the end face of the sewing machine head 3. The tape passes downwardly from the supply roll 21 through the tapered tube 20 and is folded longitudinally during its downward travel therethrough to form the piping B. The folded tape or piping B then passes beneath the downwardly curved guide finger 25 at the lower end of the tape folding tube 20, thence rearwardly over the front edge vertical opening 26 in the free end 25b of said finger and thence under the rear edge of said opening and beneath the needle 5 and presser foot 4 where it is attached to the goods C by the sewing mechanism of the machine, the tape being drawn from the supply roll by the work feeding elements 6 of said machine. The folded tape or piping B may be attached to the goods C in any desired manner, such, for instance, in the manner shown in Figs. 8 and 9, wherein the piping is embodied in the hem C' of the goods and is secured by the securing stitches C" for the hem.

The principal advantages of the above piping attachment are the easy attachment thereof to the sewing machine without disorganization thereof, the horizontal and vertical adjustments which permit the height of the free end of the guide finger to be varied and said end located in line with the line of stitching, the pivotal connection which permits the tape folding tube to be swung upwardly clear of the work table and the needle and presser foot without disturbing said adjustments, and the horizontal offsetting of the vertically disposed tape folding tube relative to the line of stitching so as to provide a clear operating space for the operator's fingers in front of the needle and presser foot.

Obviously, the hereinbefore described piping attachment admits of considerable modification without departing from the invention. Therefore, I do not wish to be limited to the precise arrangement shown and described.

What I claim is:

1. A piping attachment for an ordinary sewing machine comprising a downwardly opening upright tape folding tube adapted for mounting on said machine at one side of the line of work feed thereof, said tube having a laterally extending guide finger rigid with the lower end thereof, said finger having a vertical opening in the free end portion thereof through which the tape folded in said tube is presented in position for stitching by the needle of the sewing machine and for feeding by the work feeding mechanism thereof through said tube and along said finger and through said opening.

2. The combination set forth in claim 1, wherein means are provided for adjusting said tube vertically relative to said machine to vary the height of the guide finger.

3. The combination set forth in claim 1, wherein separate means are provided for adjusting said tube vertically relative to said machine to vary the height of the guide finger and for adjusting said tube horizontally relative to said machine transverse to the line of work feed to bring the opening in said guide finger in line with the work feeding mechanism.

4. The combination set forth in claim 1, wherein means are provided for adjusting said tube vertically relative to said machine to vary the height of the guide finger, and wherein said tube is mounted for vertical swinging movement to move said finger into and out of operative position.

5. A piping attachment for an ordinary sewing machine comprising a downwardly opening upright tape folding tube adapted for mounting on said machine entirely at one side of the work feeding mechanism thereof, said tube having a laterally extending guide finger rigid with the lower end thereof, said guide finger having a vertical opening through the free end portion thereof through which tape folded in said tube is presented in position for stitching by the needle of the sewing machine and for feeding by the work feeding mechanism thereof through said tape folding tube and along said finger and through said opening over the front edge and under the rear edge of the latter, means for adjusting said tube relative to said machine to vary the level of the guide finger, means for adjusting said tube horizontally relative to said machine transverse to the line of work feed, and means for mounting said tube for vertical swinging movement in a plane substantially parallel with the line of work feed.

6. A piping attachment for an ordinary sewing machine comprising a bracket adapted for rigid attachment to the head of said machine, an arm secured to said bracket for vertical adjustment relative thereto, an arm pivotally supported on said first mentioned arm for vertically swinging movement relative thereto in a plane substantially parallel with the work feed, a downwardly opening tape folding tube mounted on said pivotal arm and having a guide finger extending laterally therefrom in the direction of the work feeding mechanism of said machine, said finger having a vertical opening through its free end portion through which tape folded in said tube is presented in position for stitching by the needle of said sewing machine and for feeding by the work feeding mechanism thereof through said tube and along said finger and through said opening, and means for adjusting said tube horizontally relative to the pivotal supporting arm therefor transversely of the line of work feed to bring the opening in said guide finger in line with the work feeding mechanism of the sewing machine.

7. A piping attachment for an ordinary sewing machine comprising a downwardly opening tape folding tube adapted for mounting on the head of said machine in a substantially vertical position entirely at one side of the work feeding mechanism, said tube having a laterally extending guide finger rigid with the lower end thereof adapted to overhang said work feeding mechanism, said guide finger having an opening in the free end portion thereof through which tape folded in said tube is presented in position for stitching by the needle of the sewing machine and for feeding by the work feeding mechanism thereof through said tube and along said finger and through said opening.

ELMER T. COATES.
